United States Patent Office

Des. 178,962
Patented Oct. 16, 1956

178,962

COMPRESSOR UNIT FOR GASEOUS FLUIDS

John D. Johnson, Battle Creek, Mich.

Application July 21, 1954, Serial No. 31,516

Term of patent 14 years

(Cl. D65—1)

— F 1 — 1 —

— F 1 — 2 —

Figure 1 is a front perspective view of a compressor unit for gaseous fluids embodying my new design.

Figure 2 is a rear perspective view thereof.

I claim:

The ornamental design for a compressor unit for gaseous fluids, substantially as shown.
